UNITED STATES PATENT OFFICE

LLOYD D. RICHARDSON, JOHN R. TRIMMER, AND EUGENE E. LOOMIS, OF CHICAGO, ILLINOIS.

GRAIN-TRANSFER CAR.

SPECIFICATION forming part of Letters Patent No. 269,541, dated December 26, 1882.

Application filed October 9, 1882. (No model.)

To all whom it may concern:

Be it known that we, LLOYD D. RICHARDSON, JOHN R. TRIMMER, and EUGENE E. LOOMIS, residing at Chicago, in the county 5 of Cook and State of Illinois, and citizens of the United States, have invented a new and useful Improvement in Grain Weighing and Transfer Cars, of which the following is a full description, reference being had to the accompanying drawings, in which—

Figure 1 is a longitudinal vertical section, and Fig. 2 a cross-section.

The object of this invention is to improve the car patented to us September 19, 1882, and 15 to adapt a portion of our improvement to use in a smaller car by bringing the weighing-bin lower down in the car; and its nature consists in connecting the weighing-bin with the elevator, and in arranging a delivery-spout in 20 connection with the elevator so that the grain may be first delivered into the weighing-bin and afterward over it by the elevator, and in the combination of parts hereinafter described and claimed as new.

25 In the drawings, A indicates the body or frame-work of a car. The form shown is of the usual construction of a box freight-car. B are trucks; C, elevator-casing; D, elevator; E, delivery-spout; F, delivering-spout; G, weighing-bin, and H opening in the bottom thereof; I, receiving-spout for the weighing-bin; J, receiver; J', opening for a receiving-spout to connect with an adjoining car; K, frame-work of the scale, upon which the bin G is supported; 30 L, vertical boiler and engine; M, driving-belt; N, driving-pulley; O, driving-pulley for the elevator. The pulleys O and N being on the same shaft, the shaft is not shown. P is the lower wheel of the elevator; R, the balance-wheel; S, sprocket-wheel; T, chain or metal band; U, braces or trusses for the car, and V railway-rails.

The car A is of the usual box freight-car construction, except that it is provided with 45 a doorway, A', only on one side. The trucks B are also of the usual construction, except that the axle of one pair of wheels on the truck nearest the engine is provided with a sprocket-wheel or collar, so that by the use of the chain

belt T and the driving-wheel S the car may be 50 moved without the aid of a locomotive.

The engine L is of any of the ordinary constructions of upright boiler and engine, and its principal use is to drive the elevator by means of the belt M and the wheels N O, 55 which are on the same shaft, the shaft not been shown; but it may be located in bearings on top of the roof, or be supported by hangers under the roof, as may be most convenient and best adapted to the height of the 60 elevator. The wheel N may be located nearer the elevator, and the wheel R or other proper driving-wheel located in that place may be used for driving it.

The car is made sufficiently longer than an 65 ordinary box freight-car to take in the engine and machinery, as it is designed that the weighing-bin G should be sufficiently large and strong to hold the full load of an ordinary grain or box car. The bin G is made of framing and boards of sufficient strength to hold a car-load of grain, and its bottom is inclined and its parts converge to the spout or opening H, and are supported upon the timbers K of the platform weighing-scale, the bin taking 70 the place of the platform, the scale-beam and connections with the frame K, are not shown, as they are of the ordinary construction and may be located at any suitable place in or outside of the car.

Immediately beneath the opening H is located a receiving-spout, I, so arranged that the grain from the weighing-bin G may, by sliding through the bottom of the opening H, 75 flow again to the elevator.

The casing C of the elevator and the trucks B and the wheels O P are of the usual construction, and do not require a special description.

The grain is elevated and is discharged at 90 the discharge-spout E into the bin G or into the spout F, to be conveyed into a car standing upon an adjoining track. When the grain is received from an adjoining car it is directed from a suitable spouting through the opening 95 J' into the receiver J, which receiver is located below the bottom of the elevator-car and lower than the bottom of an ordinary grain-car, so

that in receiving grain from other cars it will flow easily into the receiver J; and when it is not desired to weigh the grain, but simply to transfer it, it may be passed into the receiver J, elevated, and by means of the spout F and an extension thereof delivered into an adjoining car on the opposite side of the transfer-car. The car is too low to spout grain that has been weighed into a receiving-car, so that when the grain is to be weighed it is first passed into the bin, then through the spout I into the receiver J a second time, and on such second elevation delivered through the spout F to its proper car. The spouts E and F are arranged to be connected or disconnected, according as to whether the grain is to flow into the bin G or across it into the receiving-car. This is most easily done by making the lower section of the spout F fixed to the bin, as shown, and sliding the upper section back and forth; and it will be found advisable also to provide the opening J' with a door or slide that can be closed when the grain is passing

from the bin G through the spout I to the elevator. Such door, however, will not be necessary when a permanent receiving-spout is attached to the receiver J at the opening J'.

What we claim as new, and desire to secure by Letters Patent, is—

1. The combination, in a grain-transfer car, of the bin G, having the opening H, with the spout I, elevator D, and spouts E F, substantially as described.

2. In a grain-transfer car, the combination of the receiver J, openings or spouts J' and I on opposite sides with the elevator D, bin G, scale-frame K, and delivery-spouts E F, all arranged and operating substantially as specified.

LLOYD D. RICHARDSON.
JOHN R. TRIMMER.
EUGENE E. LOOMIS.
